UNITED STATES PATENT OFFICE.

AUGUSTUS F. BRABANT AND ALFRED BRABANT, OF NEW YORK, N. Y.

DESIGN FOR A TOILET-CASE.

SPECIFICATION forming part of Design No. 21,200, dated December 1, 1891.

Application filed March 27, 1891. Serial No. 386,689. Term of patent 3½ years.

To all whom it may concern:

Be it known that we, AUGUSTUS F. BRABANT and ALFRED BRABANT, both citizens of the United States, residing in the city, county, 5 and State of New York, have invented and produced a new and original Design for Toilet-Cases, of which the following is a specification, reference being had to the accompanying drawing, forming part thereof, in which—

- 10 The drawing shows our design, which consists in a tripartite sheet of stiff material containing certain raised surfaces and ornamental figures. The three parts A A' A² are similar in size and shape, being rectangular.
- 15 Each leaf is surrounded by an ornamental border a³. The central part A is divided into rectangular portions by the transverse lines a a', the upper and lower portions being substantially equal in size and larger than the
- 20 middle portion. Arranged vertically across this middle portion are several parallel ribs or raised surfaces B, while in the upper and lower portions are rectangular figures C C' C² C³, arranged with their longer axes regis- 45
- 25 tering with the diagonals of the part A, or, in other words, radially with respect to the center of the part A. Each part A' A² contains

a figure D D', shaped like a deep Gothic arch, being in width and length about the same as the space within the border a³. Parallel with, 30 near to, and within each edge of these figures is a raised rounded rib, as shown. Those portions of the parts A A' A² not occupied by the figures described are ornamented with scrolls and other fanciful designs a². The figures 35 may be made more prominent by the use of contrasted but harmonious colors.

Having thus described our design, what we claim, and desire to secure by Letters Patent, is—

The design for a toilet-case, as herein shown and described, consisting of three similar rectangular parts A A' A², the part A having the vertical parallel ribs B and the radially-arranged rectangular figures C C' C² C³, and the parts A' A² each having the Gothic arched figures D D', each having a raised rib parallel with and near to each edge, substantially as described. 40 45
